UNITED STATES PATENT OFFICE.

ELEK LOUIS, OF NEW YORK, N. Y.

ORGAN.

1,272,821.

Specification of Letters Patent.

Patented July 16, 1918.

Application filed November 6, 1916. Serial No. 129,734.

To all whom it may concern:

Be it known that I, ELEK LOUIS, a citizen of the United States, residing at New York, in the county of New York and State 5 of New York, have invented new and useful Improvements in Organs, of which the following is a specification.

The present invention relates to electro-pneumatically operated organs, and has for 10 its main object to provide a stop mechanism, that is simple in construction and efficient in operation.

With these and other objects in view, which will more fully appear as the nature 15 of the invention is better understood, the same consists in the combination, arrangement, and construction of parts hereinafter described, pointed out in the appended claims and illustrated in the accompanying 20 drawings, it being understood that many changes may be made in the size and proportion of the several parts and details of construction within the scope of the appended claims without departing from the 25 spirit or sacrificing any of the advantages of the invention.

One of the many possible embodiments of the invention is illustrated in the accompanying drawings, in which:—

30 Figure 1 is a side elevation of a portion of an organ, including a stop mechanism constructed in accordance with the present invention; Fig. 2 is a similar elevation showing the elements in other positions; Fig. 3 is a section taken on line 3—3 of Fig. 1, on a larger scale; Fig. 4 is an end view of the detail shown in Fig. 3; and Fig. 5 is a perspective view of a rocker forming part of the stop mechanism.

40 In the drawings, the numeral 1 indicates a frame or support, on which is slidably disposed a stop-handle 2, the inner end of which is pivoted at 3 to one end of a lever 4. This lever is fulcrumed at 5, intermediate 45 its ends, to the frame, and is connected by a rod 6 with a horizontally disposed sliding stop-bar 7. The front end of this bar is pivoted at 8 to a link 9, the latter being fulcrumed at 10 to the organ frame. To the 50 rear end of the bar 7 is pivoted at 11 a contact lever 12, fulcrumed at 13 to the frame and carrying a contact piece 14, adapted to bridge the gap between two stationary contact points 15 of an electric circuit 16, into 55 which is inserted a mechanism for actuating a slide or valve. This mechanism is not

shown in the drawings as it is well known and does not form part of the present invention.

The stop-bar is provided with a longitudinal slot 17, within which is disposed a rocker 18, shown in detail in Fig. 5 of the drawings. This rocker is pivoted at 19 to the bar, and comprises a flat body including two angularly disposed portions 20 and 21, arranged 60 in such a manner that, when either one of these portions is wholly disposed within the slot, the other one projects below the underface of the stop-bar 7. A lug 22 projects above the upper edge of the rocker and co- 65 operates with a blade spring 23, or its equivalent, that is attached to the stop-bar, said spring serving to hold the rocker firmly in either one of its positions. The rocker is furthermore provided with an aperture 24, 70 through which extends a pin 26, carried by the stop-bar, said pin serving to limit the movement of the rocker in either direction.

For setting the rocker, for a purpose hereinafter to be described, there is provided a 80 vertically extending setting-bar 27, said bar being disposed in operative relation to the said rocker below the same. The setting-bar is pivoted at 28 to the movable leaf 29 of a bellows 30. This bellows is disposed 85 horizontally, as clearly appears from Fig. 1 of the drawings, and is actuated in a manner hereinafter to be described. Near its upper end the setting-bar is provided with a longitudinal slot 31, through which extends a pin 32 that is carried by the frame 1, 90 said pin and slot serving to guide the movement of the setting-bar.

For the purpose of shifting the sliding stop-bar 7 from its "off" position to its "on" 95 position and vice versa, there cooperates with the rocker 18 a mechanism, that is actuated by a vertically disposed bellows 33. This bellows is considerably larger than the bellows 30 above referred to, and has fixedly 100 attached to its movable leaf 34 an upwardly projecting lug 35, in the path of which is disposed the portion 20 of the rocker 18, when the stop-bar 7 is in its "off" position or, in other words, in a position in which 105 the contact piece 14 does not bridge the gap between the stationary contact points 15. A lever 36 is pivoted at 37 to the frame 1, its upper end being adapted to coact with the portion 21 of the rocker, when the latter 110 projects below the underface of the stop-bar. This lever is actuated also by the bellows 33,

the movable leaf 34 of which carries for this purpose a projection 38; that tilts the lever 36 around its pivot when the bellows is being inflated, in which case the upper end of the said lever moves toward the stop handle 2. A spring 39 tends to move the lever 36 in a direction opposite to that into which it is moved by the bellows 33.

13 The bellows 30 and 33 receive a supply of compressed air, for inflating the same, from a wind-chest 40. This chest is connected by pipes 41 and 42 with the bellows 33 and 30, respectively, the communication between the said pipes and the interior of the chest being controlled by a slide 43, having a single opening 44 that is adapted to register, at will, with either one of the pipes 41 and 42. Normally the opening 44 registers with the pipe 41, a spring 45, attached to the said 15 slide and to the wind-chest, maintaining the said slide in such position. For shifting the slide, in order to bring its opening 44 into alignment with the pipe 42, any suitable motor may be provided, for instance a bellows 46, to the movable leaf 47 of which is pivoted at 48 the said slide. This bellows is connected by a pipe 49 with the wind-chest 40, the communication being controlled in a manner hereinafter to be described.

20 30 From the pipes 41 and 42 lead passages 50 and 51, respectively, to an orifice 52 in one of the walls of the wind-chest, which is controlled by two valves, denoted by the numerals 53 and 54, one being disposed outside and the other one inside of the wind-chest. These valves are attached to a stem 55, the latter being secured to a diaphragm 56, covering a recess 57 in the wall of the wind-chest. This recess communicates 25 through a passage 58 with the interior of the wind-chest. The passage 58 is controlled by valve 59, the stem 60 of which is attached to a diaphragm 61, covering a recess 62 in the wind-chest, said recess being adapted to communicate through a passage 63 with the atmosphere and with the interior of the wind-chest. This communication is controlled by the armature disk 64 of an electro-magnet 65. This electro-magnet is inserted into an 30 electric circuit 66, controlled by a switch 67. The communication between the wind-chest and the pipe 49 of the bellows 46 is controlled by a mechanism similar to the one associated for the purpose with the pipes 45 and 42 and including an electro-magnet 68, inserted into an electric circuit, containing a switch 69.

60 The operation of this device is as follows:—First the operation of the means for inflating the bellows 30 and 33 will be described. As mentioned above, normally the spring 45 keeps the slide 43 in a position in which its opening 44 registers with the pipe 41, leading to the bellows 33. Compressed 65 air is supplied from any suitable source to

the interior of the wind-chest through a pipe 70, the diaphragms and valves in said chest being normally in the positions shown in Fig. 3 of the drawings, due to the fact that the same pressure prevails on both sides of the said diaphragms. If it is intended to inflate the bellows 33, the switch 67 is set to its closing position, whereby the electro-magnet 65 is energized, with the result that the armature disk 64 is attracted thereby, 70 opening the communication between the recess 62 and the atmosphere through the passage 63. The diaphragm being thus vented, the valve 59 is drawn into position to close the communication between the wind-chest and the recess 57, the said recess communicating then through the passage 58 and a vent 58' in the wind-chest wall with the atmosphere. The diaphragm 56 is thereby vented, drawing the valve 53 onto its seat 75 and unseating the valve 54. Compressed air is thus allowed to flow to the pipe 41 to inflate the bellows 33. If it is intended to inflate the bellows 30, first the electro-magnet 68 is energized, whereby the bellows 46 is inflated and the slide 43 shifted so that its opening 44 registers with the pipe 42, leading to the bellows 30. By energizing then the magnet 65, compressed air will flow through the pipe 42 to the bellows 30. From the foregoing it appears that the magnet 65 co-operates with both the bellows 30 and 33, the magnet 68 serving only to set the slide 43.

Assuming that the stop-bar 7 is in its "off" position (Fig. 1), and it is intended to shift the same to its "on" position, in which the contact piece 14 bridges the gap between the stationary contact points 15; and assuming also that the portion 21 of the rocker 18 projects below the underface of the stop bar 7, as shown in Fig. 2, and it is intended to shift the stop-bar to its "on" position, obviously, first the small bellows 30 must be inflated in order to raise the setting-bar 27, 110 whereby the rocker 18 is swung around its pivot point 19, thereby causing the portion 20 thereof to project below the underface of the said stop-bar. These positions of the elements are shown in Fig. 1 of the drawings. In order to shift now the stop-bar, the large bellows 33 is inflated, whereby the lug 35 on the movable leaf 34 thereof comes into contact with the portion 20 of the rocker and shifts the stop-bar in the direction of the arrow shown in Fig. 1 of the drawings, imparting a corresponding motion to the contact lever 12, thus bridging the gap between the stationary contact points 15.

If it is desired to shift the stop-bar from the position shown in Fig. 2 of the drawings into the position shown in Fig. 1 of the drawings, that is to say from its "on" position to its "off" position, first the rocker 18 130

must be swung around its pivot 19 so that its portion 21 projects below the underface of the stop-bar. This is accomplished by inflating the small bellows 30. When now 5 the large bellows 33 is inflated, the projection 38 swings the lever 36 into contact with the portion 21 of the rocker and, as the said lever completes its stroke, the stop-bar 7 is moved in the direction of the arrow shown 10 in Fig. 2 of the drawings.

It is obvious that, if a single stop-bar only were used in an organ action, the operations now described could be performed by simply actuating the stop-handle 2. In these 15 actions, however, a great number of stop-bars is provided, upon each of which is mounted a rocker 18, all of which are actuated by the small bellows 30 and the large bellows 33, so that, by operating the two switches 67 and 20 69, a great number of stop-bars may be shifted simultaneously, at will.

Attention is called to the fact that, inasmuch as the bellows 30 and 33 are disposed in different planes, in the case illustrated in 25 the drawings in two planes at right angles to each other, considerable space is saved compared with the structures, in which the actuating bellows are disposed in parallel planes. It is to be noted also that in the 30 device herein described, a single bellows is used for shifting the stop-bar in both directions, in contradistinction to the constructions heretofore employed in which for each direction a separate bellows is made use of.

35 What I claim is:—

1. In an organ stop action, the combination with a horizontally disposed shiftable stop-bar, of a rocker pivotally mounted on

said bar having two distinct portions extending at an angle to each other, either one 40 of said portions being adapted to project below the underface of said bar when the other one is above said underface, an actuator for setting said rocker, means adapted to co-operate with either portion of said rocker 45 for shifting said stop-bar endwise, a bellows for operating said rocker setting means, a bellows for actuating said bar shifting means, a wind-chest for supplying compressed air to said bellows, and a slide on 50 said wind-chest for controlling the communication between the latter and either one of said bellows.

2. In an organ stop action, the combination with a horizontally disposed shiftable 55 stop-bar, of a rocker pivotally mounted on said bar having two distinct portions extending at an angle to each other, either one of said portions being adapted to project below the underface of said bar when the 60 other one is above said underface, an actuator for setting said rocker; means adapted to co-operate with either portion of said rocker for shifting said stop-bar endwise, said last named means comprising a bellows, an upwardly projecting lug on the movable leaf of said bellows adapted to co-operate with one of the portions of said rocker, an oscillatable lever adapted to co-operate with the opposite portion of said rocker, and means 65 70 upon the movable leaf of said bellows for actuating said lever.

In testimony whereof, I have signed my name to this specification.

ELEK LOUIS.
